SHOW COUNTER OR DISPLAY CASE

Boris Hagelin and Birger Kock, Stockholm,
SwedenApplication December 29, 1936, Serial No. 118,146
In Sweden December 31, 1935

6 Claims. (Cl. 240—6)

This invention relates to a show counter or display case, the walls of which are made heat-insulating against the surrounding medium and the interior of which is visible from the outside through one or more windows provided in one or more of the walls and illuminated by means of a lighting arrangement disposed in a preferably longitudinally extending opening in one or more of the walls.

10 The invention consists substantially therein that the lighting arrangement consists of one or more discharge tubes, e. g. of the neon type, extending along said opening.

The invention is hereinafter fully described, reference being made to the accompanying drawings illustrating by way of example an embodiment of the invention. In the drawings:

Fig. 1 is a perspective view of the arrangement of the counter plate with the lighting arrangement being shown in a lifted-up position.

Fig. 2 is a partial cross-section of the counter close to the upper front edge with parts separated as in Fig. 1.

Fig. 3 is a longitudinal section close to the top of one of the ends of the counter.

Fig. 4 is a modified detail of Fig. 3.

The counter comprises a lower box-shaped portion 1 on which the plate 2 is placed, the latter serving as a counter for customers' service and for demonstration purposes. In its preferred form, the front wall of the counter is slightly sloping and provided with double panes 3 and 4. The top 5 of the box-shaped portion is preferably made of heat insulating material, e. g. wood, cork-stone, or the like, in which is provided an opening 6, preferably extending longitudinally and having grooves 7 and 8. On its one side the opening 6 may be bordered by the frame of the glass plates 3 and 4 forming an edge 9. If desired, the width of the opening 6 may be such that the opposite side of the opening is bordered by a corresponding edge of the rear wall.

In the opening 6 is inserted an inset 10 comprising a wood plate or panel 11 adapted to fit in the grooves 7 and 8. The underside of the plate is hollow and provided with a longitudinal reflecting surface 12. At a distance from the reflector 12, determined by optical requirements, there is disposed a discharge tube 13. This discharge tube may be of the type having a filling of rarefied gas, such as neon, helium, argon, and/or other noble gases, through which a luminous electrical discharge is passed when a direct or alternating voltage is impressed across the electrodes disposed at the tube ends. The luminous

part of the tubes does not emit any heat, or at least only an insignificant amount thereof. There is, however, a certain heating effect caused at the electrodes which has to be carried off if the interior of the counter has to remain at a low temperature. Co-extensive discharge tubes of various colour effects may be used, e. g. for producing so-called day-light illumination. The ends 14 and 15 of the tube are bent at right angles and inserted into sheet metal boxes or compartments 10 16 and 17. These are fitted into corresponding recesses 18 in the ends 19 and 20 of the counter, which ends entirely or partly consist of an insulating layer 29, e. g. of cork or cork-stone. Said recesses are bordered inwardly, for instance, by 15 fibre-plates 21. Also the outside of the recesses may consist of fibre-plates 22. In order to obtain thermal communication with the surroundings, said plates may be provided with ventilating openings 23 and a circulation opening, such as a 20 vertical duct 24, through which latter the electrical connections of the tube electrodes 25 may be drawn. This will secure the removal of the heat generated in the tube ends.

For the same purpose, according to Fig. 4, the 25 plate 25 may be provided also with a lateral opening 27 covered by a plate 26 of heat conducting material, e. g. sheet metal, for dissipating heat from the ends of the tube. This plate, too, may be provided with a ventilating opening 30 28.

If desired, the wall 22 may be entirely of sheet metal in which case heat can be conducted from the interior of the chamber 18 through the metal.

It has been proved in practice that the heat 35 eliminating devices mentioned are adequate mainly for the reason that in the discharge tubes, such as the neon-tubes, the development of heat takes place substantially only at the electrodes.

The tube 13 and/or the sheet metal box 16 may 40 be attached directly to the part 11 as shown in Fig. 3, so that when the latter is lifted the discharge tube 13 and/or the box 16 will be raised simultaneously which facilitates the upkeep or repair of the lighting device.

As shown on the drawings the opening 6 passes through only the upper wall 5 of the box shaped portion but not through the plate 2 making it possible to have the surface of the latter plane all over.

In the drawings the ends of the electrodes are shown bent at right angles and turned vertically downwards. Discharge tubes, which have their ends bent at right angles to the luminous portions of the tubes, can be mounted in various 55

ways in the display case, with the ends directed at any convenient angle to the horizontal. The structure of the display case determines, to a large extent, the best method of mounting these tubes. It is also evident that discharge tubes of various shapes may be employed without departing from the purview of this invention.

1. In the embodiment above described the opening into the display case takes up only a comparatively narrow longitudinal zone at the top of the case. However, it is also evident that this opening may be extended transversely, as desired, in order to adapt this invention to display counters of various special types.

15. We wish it to be understood that we do not desire to be limited to the exact details of construction shown and described, since obvious modifications will occur to those skilled in the art.

1. What is claimed is:

1. An illuminated show counter or display case comprising walls forming a box-like structure and having a transparent section provided in said walls, at least one gaseous discharge tube, having a luminous portion between electrode-carrying end portions which radiate relatively more heat than the said luminous portion, mounted in said box-like structure, the luminous portion of said discharge tube being in optical communication with the interior of said box-like structure without being substantially heat insulated from said interior, and heat-insulated compartments surrounding the ends of said discharge tube for shielding the interior of said box-like structure from the heat radiated from said ends only, said compartments being mounted within the confines of said box-like structure, and means for dissipating the heat from said compartments.

2. The structure of claim 1 wherein the said heat insulating compartments are ventilated in order to dissipate heat radiated from said ends.

3. The structure of claim 1 wherein the said compartments are heat insulated from the interior of said box-like structure but are in heat conducting relationship with the exterior of said structure.

4. The structure of claim 1 wherein a longitudinal opening is provided across the top of said box-like structure, wherein the said gaseous dis-

charge tube is mounted on a panel adapted to close said opening flush with the said top and wherein a slab is provided across the top of said box-like structure covering said panel and said top.

5. An illuminated and heat-insulated show counter or display case comprising heat insulating side and end walls forming a box-like structure and having a transparent section providing visibility, a gaseous discharge tube, having a luminous portion between electrode-carrying end portions which radiate relatively more heat than the said luminous portion, mounted in said box-like structure and providing illumination therefor, the said luminous portion of said discharge tube being in optical communication with the interior of said box-like structure, the end portions of said discharge tube being bent at an angle to said luminous portion and mounted in such fashion as to extend parallel to the end walls of said box-like structure, said end portions being mounted in heat-insulated compartments mounted within the confines of said box-like structure and adapted to heat-insulate said end portions from the interior of said box-like structure, and means for dissipating the heat from said compartments.

6. An illuminated and heat-insulated show counter or display case comprising heat insulating side and end walls forming a box-like structure and having a transparent section providing visibility, an elongated opening provided in said box-like structure, a panel adapted to close said opening and a gaseous discharge tube providing illumination for the interior of said box-like structure, having a luminous portion between electrode-carrying end portions which radiate relatively more heat than the said luminous portion, said discharge tube being so mounted as to be removable through said opening and with its electrode-carrying ends covered with heat insulating compartments mounted within the end walls and adapted to insulate said ends from the interior of said box-like structure, the luminous portion of said discharge tube being in optical communication with the interior of said box-like structure, and means for dissipating the heat from said compartments.

BORIS HAGELIN,
BIRGER KOCK.
